J. Kaplan
ATTORNEY.

UNITED STATES PATENT OFFICE

BEN LEWIS, OF NEW YORK, N. Y.

ATHLETIC TRUNKS

Application filed December 28, 1931. Serial No. 583,539.

This invention relates to athletic trunks.

The main object of the invention is to provide an athletic trunk which is comfortable to wear and which will not hinder the movements of the athlete.

Another object of the invention is to provide an athletic trunk having a comparatively wide heavy band at the waistline with a specially constructed reinforcement at the back.

Another object of the invention is to provide novel means to retain the reinforcing elements in the waist band.

A still further object of the invention is to provide three reinforcing elements in the belt consisting of one central resilient member bearing against the spine of the wearer and two auxiliary members bearing against the kidneys, the central member being longer than the auxiliary members.

Other objects will appear as the disclosure progresses. The drawing is intended to merely indicate a possible embodiment of the invention. It is obvious that the actual needs of manufacture may necessitate certain mechanical changes. It is therefore not intended to limit the invention to the embodiment illustrated but rather to define such limits in the appended claims. For a more general understanding of the invention attention is called to the drawing. In this drawing like reference characters denote like parts throughout the specification.

In the drawing:

Figure 1 is a front view of the pair of trunks.

Figure 2 is a rear view thereof.

Figure 3 is an enlarged fragmentary view of a portion of the rear of the trunks.

Figure 4 is an enlarged fragmentary view of a portion of the front of the trunks.

Figure 5 is an enlarged section on line 5-5 of Figure 2.

Figure 6 is an enlarged section on line 6-6 of Figure 1.

Figure 7 is an enlarged section on line 7-7 of Figure 1.

Referring now to the drawing in detail numeral 1 designates the body portion of the garment, 2 and 3 the leg portions and 4 the

belt. The belt comprises two wall members 5 and 6 sewed together at the top and bottom 7 and 8 and at the edge 9, the opposite edge 10 being open. As indicated in Figure 4 the inner wall of the belt extends beyond the edge of the outer wall 5. The meeting ends of the belt are in front of the extending portion of the wall 6 of the belt and are provided with eyelets 11 through which pass the lacing 12 for tying the belt together.

The rear of the belt is provided with an upstanding widened portion 13. Housed within the pockets 14, 15, and 16 of the said widened portion of the belt are resilient reinforcing elements 17, 18, and 19. The vertically disposed central reinforcing element 18 is longer than the elements 17 and 19 and is on line with the spine of the wearer. The last named reinforcing elements are obliquely disposed to the central reinforcing element 70 and bear on the kidneys of the wearer. Thus when the belt is tightened around the waist of the wearer the spine and kidneys will be supported and protected against any violent movements which the wearer might make 75 during the course of exercising. The rest of the garment fits loosely around the body of the athlete.

As noted in Figure 5 guides 20 and 21 are formed on both sides of the ends of the reinforcing elements to keep the said elements within the confines of the pockets and prevent the ends thereof from tearing through the pockets and injuring the wearer during the course of the exercise.

Having described my invention, I claim:

1. In a garment of the class described, the combination of a body portion, of leg portions, a belt formed of two wall members attached to the top of said body portion, the top edges of said belt turned inwardly towards one another, and reinforcing elements inserted between said turned edges.

2. In a garment of the class described, the combination of a body portion, of leg portions, a belt formed of two wall members attached to the top of said body portion, the rear of said belt being widened and provided with turned walls, and reinforcing elements in said widened portion of the belt,

the ends of said reinforcing elements housed between said inturned walls.

3. In a garment of the class described, the combination of a body portion, of leg portions, a belt at the top of said body portion, said belt composed of two wall members, the rear of said belt being widened, a vertically disposed resilient reinforcing element in the center of said widened portion of the belt, a 10 resilient reinforcing element obliquely disposed at both sides of said central reinforcing element, and the top and bottom edges of said belt turned inwardly towards each other, the ends of said reinforcing elements 15 inserted between said inturned edges.

In testimony whereof I affix my signature.
BEN LEWIS.
